FLANGE LINING MACHINE

William M. Holloway, Oak Park, Ill., assignor to
 American Can Company, New York, N. Y., a
 corporation of New Jersey

Application November 28, 1933, Serial No. 700,132

11 Claims. (Cl. 113—7)

The present invention relates to lining machines and has particular reference to machines for applying a uniform and even amount of liquid or semi-liquid lining material to the flanges of cans or can bodies.

An object of the invention is the provision of lining units in a lining machine which receive a regulated amount of lining material and which by a wiping action evenly distribute the same on the flange of a positioned can.

A further object of the invention is the provision of a lining machine of the character described which automatically propels cans having flanges to be lined through a lining operation and during such passage applies a lining material on the flanges, both the cans and the units moving continuously but along different paths.

The invention contemplates the application of a liquid lining material first to a lining pad and from the lining pad to the flange of a can, the amount of liquid put on the pad being regulated in amount and evenly spread by a wiping action onto the surface of the pad and a similar spreading and wiping action is then utilized to deposit a portion of the lining substance onto the can flange.

Another object of the invention is the provision of a lining machine which may be used in connection with a can closing machine by means of which the flange of a can is evenly covered with a lining material while in the lining machine and the newly lined can is then passed into the can closing machine so that the lined flange may be incorporated with a can end or a can cover in a seamed joint.

Numerous other objects and advantages of the invention will be apparent as it is better understood from the following description, which, taken in connection with the accompanying drawings, discloses a preferred embodiment thereof.

Referring to the drawings:

Figure 1 is a part section, part elevation of a machine embodying the present invention;

Fig. 2 is a sectional plan view taken substantially along the line 2—2 in Fig. 1;

Fig. 3 is a top plan view of the lining elements of the machine, parts being broken away;

Figs. 4 and 5 are sectional details taken respectively along the lines 4—4 and 5—5 in Fig. 2, Fig. 5 being drawn on a larger scale.

Fig. 6 is a transverse sectional elevation as viewed along the broken line 6—6 in Fig. 3; and

Fig. 7 is a sectional plan view taken substantially along the line 7—7 in Fig. 1.

In the preferred embodiment of the present

invention as disclosed in the drawings a rotating spider carries the lining pads which are supplied with a liquid or semi-liquid lining material. The charge of this liquid is applied to the pads at each cycle of operation and this application is made by a rotating roller located in the liquid. The lining pads also rotate on their own axes and in so doing produce a wiping action relative to the applying roller. The lining pads with their supporting spider are adjustable for different heights of cans to be lined.

Each lining pad is carried around in a circular path of travel by the spider and at one place is brought in alignment with the can body which is being conveyed continuously through the apparatus. A portion of the can path coincides with the path of the lining pad to effect such alignment and at such a time and during the uninterrupted advancement of both can and pad the latter descends and with a wiping action caused by the constant rotation of the pad about its own center delivers a film of lining material on the top flange of the can below. The pad is then raised and the can body is conveyed from the lining apparatus.

The lined can is now in condition for attachment to a can end or cover and may be immediately conveyed into a double seaming machine such an association being disclosed in the drawings. The term "can" is used in its broad sense and designates either a can having a bottom or only a can body, either of these being lined in the same identical manner.

The lining pads and their supporting spider are carried in a frame 11 (Figs. 1 and 2) which may be a part of or which may be closely associated with a double seamer generally indicated by the numeral 12. In the drawings the frame 11 is shown as being bolted at 13 directly to the double seamer and this frame 11 is also indirectly supported on a column 14 which provides a more rigid structure.

The lining pads, indicated generally by the numeral 15, are carried on the lower ends of vertical shafts 16. Each shaft is carried by the spider which is indicated by the numeral 17 and this spider is carried by the frame 11 as will be hereinafter more fully described. Cans or can bodies 21 to be lined are introduced into the machine (Figs. 1 and 2) and each can is formed with a flange 22 at the top and these cans or can bodies are continuously advanced from the time they are first introduced into the machine until they pass into the double seamer 12.

The cans 21 are brought into the machine in any suitable manner as by conveyor chains 25 which operate in a can feed table 26 carried on the frame 11. Each chain 25 at the machine end operates over an idler sprocket 27 (Figs. 4 and 6) and is moved in any suitable manner. Each sprocket 27 rotates over a horizontally disposed shouldered stud 28 which is threadedly secured in a vertical wall of the feed table 26.

10 The cans 21 ride on and are carried forward by the upper runs of the chains 25 and at such time are retained in a straight line of travel by guide bars 29, 31 (Figs. 1 and 2) carried on brackets 32 mounted on the feed table. Both of these guide bars, however, extend beyond the conveyor chains 25 through a lining station A and on into the closing machine 12. The forward or closing machine sections are supported on a feed table 33 of the closing machine, brackets 34 being used for holding the guides on the table.

15 The can 21 advanced by the chains 25 as it approaches their inner ends, that is, as it moves over the sprockets 27, is pushed off of the chains and onto a continuously revolving can carrier disc 41. The can is still retained within the guide bars 29, 31.

20 At the lining station A the can now carried on the disc 41 passes along part 42 of the guide rails 29, 31 and is thereupon shifted from its straight line of travel and is caused to move along the path of a reversed curve, this being the form of the rail part 42. The forward end of the curved section merges into the straight forward end sections of the guide rails 29, 31 on the closing machine table 33. It is during this passage of the can along the curved guided rail section 42 that its top flange 22 is engaged by a lining pad 15 moving around the spider 17 and upon such engagement lining material on the pad is transferred to the flange of the can.

25 The disc 41 is formed on the upper end of a vertically disposed sleeve 45 (Fig. 1) which is journaled in a bearing 46 formed in the frame 11. The disc 41 is enlarged as a hub 47 where it merges into the sleeve 45 and it is this hub that rests upon the top of the frame bearing and by means of which the disc, sleeve, etc., are retained at the proper level. The disc 41 with its sleeve 45 is continuously rotated in any suitable manner as by suitable driving power applied to a lower gear 48 keyed on the lower end of the sleeve and locked in place by a lock nut 49 threadedly secured thereto.

30 The spider 17 with the lining pads 15 are rotated in unison with the disc 41 and for this purpose a sleeve 51 is located inside of the disc sleeve 45 and extends above and below the disc sleeve. Sleeve 45 is provided with a longitudinally disposed featherway 52 which extends from near the bottom sleeve end up into the disc hub 47. A feather 53 is carried in this featherway and has slight movement in a corresponding featherway 54 cut longitudinally of the sleeve 51. This construction insures uniform rotation of the two sleeves while permitting vertical movement of the inner sleeve 51 within the disc sleeve 45.

35 The spider 17 is carried on and is keyed to the upper end of the sleeve 51 and inasmuch as this spider carries the lining pads and parts associated therewith, the position of the sleeve 51 within the disc sleeve determines the height of the lining units which height is set in accordance with the height of can being lined. Where a taller can is to be lined it is merely necessary to

raise the sleeve 51 within the disc sleeve 45 in order to bring the lining pads 15 to a higher level. An easy adjustment of the spider and parts carried thereby is provided for and consideration will now be given to this feature, reference being had to Fig. 1.

40 A vertical stationary shaft 55 extends through the sleeve 51 and projects both above and below it. This shaft is threaded at its lower end at 56 and carries a collar 57 pinned in fixed position to the shaft on which the sleeve 51 rests. The weight of the sleeve, the weight of spider and parts carried thereby are supported at all times upon this collar.

45 The shaft 55 is held in a bracket 61 which is secured to the frame 11. This bracket is formed with spaced bearings 62 in which the lower threaded section 56 of the shaft 55 is loosely positioned. A hand wheel 63, internally threaded, threadedly engages the shaft end 56 intermediate the bearings 62 and this hand wheel carries the weight of the shaft and through it the weight of the spider 17, sleeve 51 and the lining units. The shaft end 56 is cut longitudinally with a featherway 64 and a feather 65 is preferably located in each bearing 62. This construction allows for vertical movement of the shaft 55 but prevents its rotation. Turning of the hand wheel 63 on the shaft 55 raises or lowers the shaft and the lining parts carried thereby as desired depending upon the direction of rotation of the hand wheel. The weight of these parts effective on the engaged threads firmly holds the handwheel against accidental or unintentional movement.

50 The upper end of the stationary shaft 55 is reduced in diameter to form a stem 71 and a shoulder at the junction line between the two diameters. This stem carries a split collar 72 which rests on the shoulder and an enlarged lower section of the collar is located in a recess 73 formed in the upper end of the central hub part of the spider 17. A ring 74 is secured by screw 75 to the spider and in cooperation with the recess forms a movable joint at this place. The collar 73 is keyed to the stem 71 and so is also held stationary while the spider 17 and the ring 74 rotate with the sleeve 51.

55 The stem 71 also carries a gear 76 which rests upon the collar 73 and which is also keyed to the stem. A ring cam 77 is mounted upon the stem 71 above the gear 76 and this cam is also held in stationary position, being also keyed to the stem. A washer 78 and a lock nut 79 mounted on the upper end of the stem holds 60 collar, gear and cam together as a single stationary unit.

60 The spider 17 carries three vertically disposed hubs 81 (Figs. 1 and 3) which are equally spaced around the periphery of the spider upper wall 65 and one of the rods 16 is carried in each hub. A gear 82 is formed as an integral part of and is located at the top of a vertically disposed sleeve 83 and each of these sleeves is journaled for rotation within one of the spider hubs 81. Each 65 sleeve 83 is also threaded at its lower end and a lock nut 84, located just below the hub bearing 81, is threaded on the sleeve and this holds sleeve and gear against any vertical movement within the bearing.

70 Three idler gears 85 are carried on the top wall of the spider 17 and each gear is pinned to the upper end of a short vertical shaft 86 which is journaled in a boss 87 formed in the spider wall. The lower end of each shaft 86 extends below 75

its boss 87 and a collar 88 pinned to the shaft maintains the latter in rotatable position within its hub. Each idler gear 85 meshes with the stationary gear 76 and as the spider rotates the gears 85 are caused to move around the center stationary gear and are thereby rotated.

Each idler gear 85 also meshes with one of the gears 82 and as the former rotates the latter is correspondingly rotated. Each rod 16 within its sleeve 83 carries a feather 81 which has sliding movement within a featherway 82 cut on the inside of the sleeve and the gear 82. This permits vertical shifting of the rod 16 relative to the sleeve while insuring unit rotation of the two parts. This is the way and manner the lining pads 15 are continually rotated on their axes.

The lower end of each rod 16, where it unites with its lining pad, is reduced to form a stem 93 which engages in a holder body 94 of a lining unit, the lower end of the stem being riveted over at 95 to secure the holder firmly in place. An absorbent pad 96 is carried in each holder 94 being removably held in place by a clamp plate 97 located inside of the absorbent material and clamping its outer edge within the holder, this clamp plate being held within the holder by bolts 98. The lower surface of the pad 96 is the element of the lining unit which engages with the flange 22 of the can 21 during the lining operation.

In one cycle of movement of a lining pad 15, that is, during a single rotation of the spider 17, the pad is caused to pass over a supply roller operating in a fixed tank or reservoir and is also brought into alignment with the can as it passes along the curved rail section 42 of the guide rails 29, 31 which has just been described. Each lining pad has a raised and a lowered position and when a pad passes over the applying roller it is in its upper position. When passing through the lining station it is caused to descend into lining position.

This difference in horizontal position is brought about by a raising and lowering of the rod 16 associated with a lining unit. For this purpose each rod 16 at its upper end and above the gear 82 carries a block 101 (Figs. 1 and 3) which is loosely mounted on the rod being held in place by spaced collars 102 pinned to the rod. Each block 101 projects inwardly toward the center of the shaft 55 and is formed with a curved face 103 which slides along the outer periphery of the stationary cam 77. This curved face 103 of the block 101 prevents rotation of the block 55 with the rotating rod 16.

Each block 101 adjacent its curved face 103 carries a cam roller 104 which is loosely mounted on a pin 105 fixed in the block. This cam roller traverses a cam groove 106 formed in the periphery of the stationary cam 77. The cam track 106 is shaped to hold the roller 104, and through it the lining pad 15 associated therewith, in the proper level, that is, up for receiving the lining material on its absorbent pad 96 or down for bringing it into engagement with the flange of the can in the lining operation.

The lining material which is liquid or at least semi-liquid is retained within a reservoir indicated generally by the numeral 111 (Fig. 2). This reservoir is held in a stationary position above the disc 41 and is offset or at one side of the path of travel of the cans passing along the guide rails 29, 31. The reservoir 111 comprises a tank 112 (see also Figs. 1 and 6) and this tank is supported in an adjustable position

on the frame 11 and is raised or lowered for different can heights to always keep it in an exact position relative to the lining pads.

For this purpose the tank 112 is formed with a pair of spaced depending bosses 113 which rest upon the shouldered upper ends of vertically disposed rods 114, each rod being reduced at its top end in a stem 115 which passes through its corresponding boss 113. The rods are held in locked position on the tank by lock nuts 116. Each rod 114 is a loose fit in a boss 117 formed in a bracket frame 118 (Fig. 7) bolted to the frame 11. Lock nuts 119 are threadedly secured on each rod 114 one above and one below its bearing boss 117 and these cooperate to hold the rod in any desired adjusted vertical position. On the opposite side the tank 112 projects inwardly at 120 (Figs. 1 and 2) where it loosely engages around the sleeve 51. This assists in holding the tank more rigidly.

The liquid lining material is lifted from the reservoir and is applied to the lower surface of the absorbent pad 96 by an applying roller 121 (Figs. 1 and 2). This roller is carried on a horizontal shaft 122 journaled in outer and inner bearings 123 formed in the tank, the inner bearing being located on the tank projection 120. The applying roller is continuously rotated with its shaft 122 and for this purpose the outer end of the shaft extends beyond the outer bearing 123.

The shaft 122 carries a gear 124 which meshes with a similar gear 125 pinned to the upper end of a vertical shaft 126. Shaft 126 is journaled adjacent its upper end in a boss 127 formed in the reservoir tank frame 112 and centrally of the bosses 117. The shaft 126 at its lower end extends into a gear 128 which is elongated at its lower end in an integral sleeve section 129. This sleeve is journaled in a bearing 131 formed in the bracket frame 118 (see also Fig. 7).

The gear sleeve 129 is threaded at its lower end where it projects beyond the bearing 131 and a nut 132 is threadedly secured in that position, this construction holding the gear 128 and sleeve 129 against vertical movement within the boss 131. When the reservoir 111 is raised or lowered as previously described the shaft 126 is correspondingly raised or lowered and at such time slides inside of the gear 128. The shaft 126 carries a feather 133 which slides in a featherway formed longitudinally of the shaft and by means of this construction the rotating cooperation between gear and shaft is maintained and insures unit movement of shaft and gear.

The gear 128 meshes with a gear 134 which is carried on and pinned to one end of a horizontal shaft 135 journaled within a bearing 136 formed in the bracket frame 118. The opposite end of the shaft 135 carries a gear 137 which meshes with a gear 138 secured to the upper end of a vertical shaft 139. The shaft 139 is mounted upon and moves within a bearing 141 formed in the bracket frame 118.

A collar 142 is pinned to the lower end of the shaft where it projects below its bearing and into the upper hollow end of the supporting column 14 and this prevents vertical movement of the shaft. The shaft 139 also carries a gear 143 which is located just below and which may be an integral part of the gear 138. The gear 143 meshes with the drive gear 48 and in this manner driving power is imparted to the lining roller 121.

The continuous rotation of the applying roller 121 lifts a film of lining compound from the

reservoir and applies it to each absorbent pad 96 when a pad passes over the roller. Such a passage and the transfer of the lining material onto the pad surface is accompanied by a wiping 5 action as the pad moves along its circular path across the upper face of the roller and also as the rotating pad is moving on its own axis. This assures a more even distribution of the lining material upon the lining pad. In addition to the 10 wiping and distributing feature provision is also made for regulating the thickness of the film left on the applying roller 121.

A scraper blade 151 is adjustably secured (Figs. 2 and 5) on a bridge member 152 which extends 15 across the tank 112 having projections 153 which rest on the opposite side walls of the tank where they are secured in position. The blade 151 is slotted at 154 and the enlarged head of a screw 155 engages within the slot 154. There are two 20 of these screws 155 and two corresponding slots 154 in the blade.

Each screw 155 is threadedly secured in a central rib 156 formed in the bridge 152 and rotation of a screw within its slot gives a fine adjustment 25 to the blade 151 by drawing that side of the blade forward or back. An exact thickness of film of compound raised by the rotating roller 121 is in this manner obtained. Screws 157 pass through slots formed in the blade and are threadedly held 30 in the bridge 152 and these screws are used to lock the blade in its adjusted position.

To avoid unevenness of lining material on the absorbent pad 96 by a repeated piling up of material from one cycle to another provision is made 35 for scraping the entire lower surface of the pad clean at each cycle of operation and just before a new charge is put on by the roller 121. For this purpose a scraper 161 is secured to the rib 156 and its upper edge is vertically adjustable by 40 means of which it may be placed to drag across the lower part of the pad as it moves over the reservoir and before it comes into engagement with the applying roller 121. This scrapes the pad clean each time and presents a new or clean 45 surface.

A pair of pointed adjusting screws 162 are threadedly secured in the bridge 152 at the back part of the reservoir the tapered ends of these screws engaging a tapered lower edge of the 50 scraper blade 161. By moving the screws in, the blade is pushed up on the rib 156 and a very fine and accurate adjustment is thus possible. After it has been properly located the blade is clamped in its adjusted position by screws 163 which pass through slots formed in the blade and which 55 threadedly engaged within the rib 156. A lock nut 164 threadedly engaging each of the adjusting screws 162 may be used for holding these screws in their adjusted positions.

Reference has already been made to the fact 60 that a can after it has received the lining material on its flange 22 continues its advancement through the guide bars 29, 31. At the lining station A the can is brought under the influence of the feeding devices associated with the closing machine and these then control its travel and remove it from the disc 41.

As one example of feeding devices which have 70 been found satisfactory for this purpose there is illustrated in the drawings a chain conveyor 171 which operates in suitable grooves formed in the seaming table 33. This chain carries a series of pivoted can propelling arms 172. Each arm is rocked on its pivotal mounting on the chain through the action of a cam track 173 along

which a cam roller 174, carried by the arm, is moved. The chain 171 may operate over a sprocket 175 adjacent the lining mechanism and this sprocket is preferably mounted on a vertical shaft 176 journaled in suitable bearings formed in the closing machine table 33.

The shaft 176 (Figs. 4 and 7) may receive rotation directly from the drive gear 48 through a train of gears enclosed within the housing 11. The shaft 176 carries a gear 177 which meshes 10 with an idler gear 178 rotating on a stud 179 secured in the frame 11. Gear 178 also meshes with a second idler gear 181 loosely mounted on a stud 182 also carried in the frame 11. The gear 181 15 meshes with the drive gear 48 and in this manner the conveyor chain 171 is synchronized with the lining machine and properly advances an arm 172 so that it will engage behind the can at the lining 20 station A and will slide it off of the disc 41 and thence convey it along the closing machine table 25 33 while the can is confined in its path by the guide rails 29, 31.

The lined can is in this manner advanced to a seaming station B (Figs. 1 and 2) where it may be placed upon a lift plunger or other suitable support 181 which lifts it into seaming position within a seaming head 183 in the usual manner. During the seaming operation the arm 172 is backed off relative to the advancing chain 171 by being pivoted on its mounting through the action of the 30 cam roller 174 and the cam track 173. The seaming operation thus takes place without stopping the conveyor chain 171. This construction is well known and it is believed further description is unnecessary for the purpose of the present invention. It will be understood that a can end or cover is brought into the seaming station in the regular way, this being a feature of the closing 35 machine itself.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

I claim:

1. In combination, a machine for lining can flanges with a lining material, comprising a support for a can to be lined, a lining pad movable into aligned position over said can while on said support, rotary means for applying lining material to said pad, means for causing said pad to engage the said can flange and to deposit lining material thereon, and means for rotating said pad during said application to give a wiping action and to evenly distribute the applied material on the said can flange.

2. In a machine for lining can flanges with a lining material, the combination of a support for a can to be lined, a lining pad movable bodily in a circular path into aligned position over said can while on said support, a reservoir for holding lining material, a roller rotatable in said reservoir for applying lining material to said pad, means for causing said pad to engage the said can flange and to deposit lining material thereon, while in said aligned position, and means for rotating said pad during such application to provide a wiping action for evenly distributing the applied material on the said can flange.

3. In a machine for lining can flanges with a lining material, the combination of a can feed-

ing device for feeding cans having flanged ends to be lined, a lining pad bodily movable in a circular path over the path of said can while in said feeding device, a reservoir for holding lining material, a roller rotatable in said reservoir for applying lining material to said pad, means for causing said pad to engage the said can flange and to deposit lining material thereon, and means for rotating said pad during such application to give a wiping action to the lining operation and to evenly distribute the applied material on the said can flange.

4. In a machine for lining can flanges with a lining material, the combination of a support for a can to be lined, a lining pad bodily movable in a circular path over said support, a reservoir located adjacent said support for holding lining material, a roller rotatable in said reservoir for applying lining material to said pad, means for causing said pad to engage the said can flange and to deposit lining material thereon, means for rotating said pad to effect a wiping action relative to the can flange during the lining operation, and cleaning means for removing the excess lining material left on said pad after the lining operation.

5. In a machine for lining can flanges with a lining material, the combination of a can feeding device for feeding a can having a flanged end to be lined, a rotatable spider located above said can feeding device, a lining pad carried by said rotatable spider and movable over the path of said can while in said feeding device, a reservoir for holding lining material, means for moving said pad over said reservoir and for applying a lining material thereto, means for causing said pad to engage the said can flange and to deposit lining material thereon while the said pad is over said can path, and means for rotating said pad during such application to give a wiping action and distribute the applied material on the can flange.

6. In a machine for lining can flanges with a lining material, the combination of a support for a can to be lined, a lining pad movable into aligned position over a said can while on said support, a reservoir for holding lining material, means for moving said pad over said reservoir, a roller rotatable in said reservoir for applying lining material to said pad during its movement over said reservoir, the application of said material being effected with a wiping action to evenly spread the material on said pad, means for causing said pad with its applied material to engage the said can flange and to deposit lining material thereon, and means for effecting a wiping action of said pad relative to the can flange to evenly distribute the applied material thereon.

7. In a machine for lining can flanges with a lining material, the combination of a support for a can to be lined, a lining pad movable bodily in a circular path into aligned position over said can while on said support, a reservoir for holding liquid lining material, a roller rotatable in the liquid in said reservoir for applying lining material to said pad in a thin film, means for regulating the thickness of said film on said roller, means

for causing said pad to engage the said can flange and to deposit the lining material thereon while in said aligned position, and means for continuously rotating said pad to first evenly distribute the said film of lining material thereon and thence to evenly distribute the said material on said can flange.

8. In a machine for lining can flanges with a lining material, the combination of can feeding devices for feeding cans having flanged ends to be lined first to a lining station and thence to a seaming station, a lining pad movable over the path of said can while in said feeding devices, means located at said lining station for applying a lining material to said pad, means for causing said pad to engage the said can flange and to deposit lining material thereon, means for rotating said pad during such application to provide a wiping action and to evenly distribute the applied material on the said can flange, and seaming means located at said seaming station for securing a can end on said can with a said lined flange incorporated in said seam.

9. In combination, a machine for lining can flanges with a lining material, comprising a support for a can to be lined, a lining pad movable into aligned position over said can while on said support, rotary means for applying lining material to said pad, means for causing said pad to engage the said can flange and to deposit lining material thereon, and means for adjusting the height of said lining pad and said lining material applying means relative to said support to provide for lining cans of different heights.

10. In a machine for lining can flanges with a lining material, the combination of a support for a can to be lined, a lining pad movable bodily in a circular path into aligned position over said can while on said support, a reservoir for holding lining material, a roller rotatable in said reservoir for applying lining material to said pad, means for causing said pad to engage the said can flange and to deposit lining material thereon, while in said aligned position, and means for adjusting the height of said lining pad, reservoir and applying roller relative to said support to provide for lining cans of different heights.

11. In a machine for lining can flanges with a lining material, the combination of a can feeding device for feeding cans having flanged ends to be lined, a lining pad movable bodily in a circular path over the path of said can while in said feeding device, a reservoir for holding lining material, a roller rotatable in said reservoir for applying lining material to said pad, means for causing said pad to engage the said can flange and to deposit lining material thereon, means for rotating said pad during such application to evenly distribute the applied material on the said can flange, and means for adjusting the height of said lining pad, reservoir and applying roller relative to said support to provide for lining cans of different heights the while maintaining said pad rotating means in operative position.
